Primary Examiner — Vy N Koenig*Assistant Examiner* — Kimberly Barnes(74) *Attorney, Agent, or Firm* — Calfee, Halter & Griswold LLP(57) **CLAIM**

The ornamental design for a shingle, as shown and described.

DESCRIPTION

FIG. 1 is a front isometric view of a shingle, showing our new design;

FIG. 2 is a right side elevation view of the shingle of FIG. 1;

FIG. 3 is a top plan of the shingle of FIG. 1;

FIG. 4 is a front elevation view of the shingle of FIG. 1; and, FIG. 5 is a rear elevation view of the shingle of FIG. 1.

The broken lines in the figures depict portions of the shingle that form no part of the claimed design.
